UNITED STATES PATENT OFFICE.

HUBERT C. HART, OF UNIONVILLE, CONNECTICUT.

HEELING-MACHINE.

SPECIFICATION forming part of Letters Patent No. 450,755, dated April 21, 1891.

Application filed March 31, 1890. Serial No. 345,955. (No model.)

To all whom it may concern:

Be it known that I, HUBERT C. HART, residing at Unionville, in the county of Hartford and State of Connecticut, have invented 5 certain new and useful Improvements in Heeling-Machines; and I do declare the following to be a full, clear, and exact description of the same, reference being had to the accompanying drawings, which form a part 10 of this specification.

My invention relates to an improvement in that class of machines for heeling boots and shoes in which the nails are first assembled in the top lift and the same then forced down 15 upon the body of the heel, through which the nails are thus driven and into the shoe, its leading object being to provide effective means for holding the top lift in its right relation to the nail-holder in which the nails 20 are assembled and in guiding it as it is forced down upon their projecting ends.

With this object in view my invention consists in a vertically - movable adjustable clamp and in certain details of construction 25 and combinations of parts, as will be herein-after described, and pointed out in the claims.

In the accompanying drawings, Figure 1 is a view in front elevation of a heeling-machine embodying my invention, the parts 30 thereof being in the positions due to them before the descent of the presser upon the top lift. Fig. 2 is a similar side view of the machine, the parts being in the same positions. Fig. 3 is a broken view in vertical section 35 showing the clamp and last and the top lift forced down by the presser. Fig. 4 is a similar view, with the nails assembled in the nail-holder and the top lift resting upon their projecting ends in position to be driven down 40 upon them by the presser; and Fig. 5 is a detached plan view of the swinging nail and heel holder.

The frame-work of my machine consists of a stationary horizontal bed-plate A, an upper sleeve B, and two upright rods C C, secured to the bed-plate and united at their upper ends by a cross-piece D, forming a support for the stop E of the awl-stripper M. A heavy plunger F, located within the said sleeve 45 B, is reciprocated, as herein shown, by means of a horizontal shaft G, journaled in hangers H H', depending below the bed-plate A, be-

fore mentioned, and provided with a wrist-pin I, operating a link I', pivoted to the lower end of the plunger; but, if desired, the shaft 55 may be reciprocated by hand or in any other suitable way by power.

A horizontal carrier J, secured to the upper end of the plunger, has two arms L and L' projecting in opposite directions, and an intermediate arm L². The said arms L² and L', respectively, carry the pressers N and N', each composed of a flat head and a spindle, the office of the former being to crowd the top lift v down upon the nails after the nails 60 have been assembled in the nail-holder Q, and of the latter to drive the top lift and nails r down upon the heel-body, at the same time securing the latter to a boot or shoe. The said nail-holder is provided with a number 65 of deep pockets arranged conformably with the final arrangement of nails in the completed heel and adapted to support the nails with the upper ends of the same projecting beyond its upper face, the pockets being 70 shorter than the length of a nail. The said arm I carries the awl-head M and its stripper M', the spindle M² of the latter extending upward through the awl-head and arm into position for engagement with the 75 adjustable stop E, before mentioned. An anvil O, located directly beneath the said awl-head M and the stripper M' thereof, is mounted upon a vertically-adjustable stud forming a part of a carriage O', provided with a man- 80 ual O² and dovetailed upon the bed-plate A for longitudinal reciprocation thereupon 85 between guides o and o'.

The last P of the machine is mounted upon a carriage P' similar in construction and operation to the carriage O', above described. 90 These carriages are like corresponding parts in Patent No. 410,832, granted to me September 10, 1889, and do not need extended explanation here.

The nails r r, which are used in connection with this machine, have shoulders and ends projecting beyond the same a sufficient distance to carry the top lift of a heel-body. The nails are first assembled in the nail-holder Q, then the top lift is placed upon the projecting ends, as shown by Fig. 4 of the drawings, and finally the presser N is brought 100 down upon the top lift and the same forced

over the said ends of the nails, which are thus assembled with the top lift. The nails and top lift are then assembled with a heel-body and a boot or shoe upon the last P, after 5 which the presser N' is brought down upon the top lift with the effect of forcing the same down upon the heel-body and the nails through the said heel-body and into the boot or shoe.

10 For convenience in centering the top lift upon the ends of the nails and to guide the same when being forced down upon the same by the stamper, I have provided a vertically-movable spring-supported clamp adapted to 15 be adjusted to heels of different sizes and combined with the nail-holder Q and the carriage Q' thereof, the said carriage being swiveled upon the bed-plate A of the machine by a stud q', and provided with a manual q², by 20 means of which the carriage is swung to bring the nail-holder Q to its normal position under the presser N and to withdraw it from that position. The said clamp consists in part of 25 two spring-arms y and y', pivoted at their lower ends in vertical slots respectively formed in the opposite ends of a head R, mounted for vertical movement upon the post g³, carrying the nail-holder Q and forming a part of the carriage Q'. The upper end of the arm y is 30 formed with a bearing-face a made straight to conform to the straight inner edge of the top lift, while the upper end of the arm y' is formed with a transverse bearing-finger a', made curved to conform to the curved outer 35 edge of the top lift, which is placed between the said upper ends of the two arms. The said head rests upon the upper end of a spiral spring S encircling the part g³, supported upon a part of the carriage Q' and exerting a 40 constant tendency to lift the head and so raise the arms into the positions which they occupy in Fig. 4 of the drawings. A thumb-screw d, having a shoulder e formed at its outer end and a corresponding thumb-screw 45 d', having a similar shoulder e', are respectively passed through the lower ends of the said arms, so that these shoulders engage with the outer faces thereof, their inner ends being threaded into the opposite ends of the 50 head R, which the arms are normally held away from by means of small spiral springs f and f' encircling the inner ends of the screws and interposed between the block and the arms. These set-screws d and d', together 55 with set-screws g and g', mounted in the upper ends of the arms and bearing against the nail-holder at opposite points thereupon, are provided for adjusting the spread of the arms to top lifts of different sizes. Normally the 60 upper ends of the arms extend above the nail-holder in position to receive a top lift between them when the same is rested upon the projecting ends of the nails in the holder, the lift being by them held in its right relation to 65 the nails. Now when the presser N descends upon the lift it engages with the upper ends of the arms and forces the same to retire as

rapidly as the lift is crowded down upon the nails. During this time the clamp, or, more properly, the arms, guide the lift and insure 70 its right assemblage with the nails. When the arms retire, as described, the spring S is compressed; but upon the return-stroke of the spring it at once restores them to their normal position of readiness to receive another lift. The clamp is thus organized with 75 the nail-holder in the sense that both are mounted upon the same carriage, but the clamp is also movable independently of the nail-holder. 80

Rubber cushions U U, respectively interposed between the presser N and its arm L² and the presser N' and its arm L', are provided to compensate for variations in the thickness of the top lift, whereby the machine is prevented from pounding from that 85 or other causes.

The awl-head M, the stripper M', the stop E, and the anvil O are provided for piercing the heel-bodies preparatory to being placed 90 upon the last to receive the nails, top lift, and to be secured to the boot or shoe. When the awls have passed into the heel, the same is stripped from them by the stripper M', the spindle M² whereof engages with the stop E, 95 supported from the posts C C'. In my patent herein referred to the stop is shown as supported by an arm secured to the sleeve, in which the vertically-acting plunger is located; but I prefer the construction herein 100 shown as being stronger and as relieving the plunger from all friction so far as the stop is concerned.

To provide for using the machine in making and applying heels with shoulderless 105 nails of the old form, I have furnished it with a heel and nail holder consisting of an arm X, mounted on the rod C, so as to be swung over and away from the anvil O, and provided at its outer end with a series of vertical nail-holes a², extending through it and corresponding in arrangement to the arrangement of nails in a heel. The said arm is also provided with four springs b², secured to its under face and adapted to hold a heel-blank 115 c² against the same, whereby nails placed in the nail-holes are prevented from dropping through the same. When the arm has been charged with nails and a heel-blank, it is 120 swung over the anvil O, after which the nails are driven into the heel-blank by means of drivers substituted for the awls in the awl-head M, the drivers and anvil being set so that the heads or outer ends of the nail will 125 be left projecting from the blank for the attachment of the top lift on the last P.

The features in which this machine is an improvement over that in the patent referred to are believed to be novel, broadly; and I therefore hold myself at liberty to make such 130 changes and alterations in the specific construction herein shown as fairly fall within the spirit and scope of my invention.

Having fully described my invention, what

I claim as new, and desire to secure by Letters Patent, is—

1. In a heelng-machine, the combination, with a nail-holder provided with pockets entering it from its upper face and shorter than the length of a heel-nail, of a movable clamp organized with the nail-holder and normally extending above the upper face thereof to center a top lift above the same, and a presser 5 to depress the clamp and crowd a top lift down over the projecting outer ends of nails inserted into the nail-holder, from which they are afterward withdrawn by means of the top lift, which has thus been attached to them, 10 substantially as described.

2. In a heelng-machine, the combination, with a nail-holder provided with pockets entering it from its upper face and shorter than the length of a heel-nail, of a movable clamp 20 organized with the nail-holder and normally extending above the upper face thereof to center a top lift above the same, a spring to support the clamp in its normally-elevated position of readiness to center a top lift, as 25 described, and a presser to depress the clamp and crowd a top lift down over the projecting outer ends of nails inserted into the pockets of the nail-holder, from which they are afterward withdrawn by the top lift, which 30 has thus been attached to them, substantially as described.

3. In a heelng-machine, the combination, with a nail-holder provided with pockets entering it from its upper face and shorter than 35 the length of a heel-nail, of two vertically-arranged arms, the upper ends whereof are bowed and normally extend above the upper face of the nail-holder, while their lower ends extend below the same, a movable support 40 having the lower ends of the said arms pivotally connected with it, a spring located below the said support for supporting the said arms in their normal positions, a presser to crowd a top lift down over the projecting 45 outer ends of the nails in the nail-holder, and means for connecting the upper ends of the arms with the said nail-holder, substantially as described.

4. In a heelng-machine, the combination, 50 with a vertical post, of a nail-holder mounted upon the upper end thereof and provided with pockets entering it from its upper face and shorter than the length of a nail, a vertically-movable head encircling the post below the nail-holder, two spring-arms pivoted

at their lower ends to the said head and normally extending above the upper face of the nail-holder and bowed at their upper ends to clamp a top lift and center it over the same, a spring for supporting the head, and hence 60 the arms, set-screws extending through the said arms at their upper and lower ends and co-operating with the nail-holder and the movable head to adjust the position and tension of the arms, and a presser to crowd a 65 top lift down upon the projecting outer ends of nails inserted into the pockets in the nail-holder, from which the nails are then withdrawn by the top lift which has thus been attached to them, substantially as described. 70

5. In a heelng-machine, the combination, with an upright plunger, of a horizontal carrier secured to the upper end thereof, a centrally-perforated awl-head secured to the lower face of one end of the said carrier, 75 which is vertically perforated in alignment with the perforation of the head, a stripper located below the awl-head and in line therewith, and provided with a spindle extending upward through the perforations in the awl-head and carrier end and projecting above the latter, an adjustable stop located above the upper end of the said spindle and in position for engagement thereby, a horizontal cross-bar carrying the said stop, and two 80 heavy upright rods mounted in the bed-plate of the machine and supporting the cross-bar carrying the said stop, substantially as described.

6. In a heelng-machine, the combination, 90 with an anvil, of a combined nail and heel holder consisting of a horizontal rotatable arm provided with a series of vertical holes extending transversely through it, and with springs projecting below its lower face and arranged 95 to hold a heel-blank up against the same to prevent the nails from dropping through the holes therein, an upright support on which the said combined nail and heel holder is swiveled, and a vertically-reciprocatable head 100 for carrying nail-drivers arranged conformably with the holes in the nail and heel holder, substantially as described.

In testimony whereof I have signed this specification in the presence of two subscribing witnesses.

HUBERT C. HART.
